Application April 17, 1944, Serial No. 531,389

19 Claims. (Cl. 179—84)

1

The present invention relates to telephone systems in general, and more particularly to improved circuits for automatic individual-line ringing, automatic party-line ringing, and quick ringing cut-off in manual and automatic telephone switchboards.

An object of the invention is to provide new and novel circuit arrangements for applying and disconnecting automatically-interrupted ringing currents to and from a plurality of connecting circuits in a telephone system.

Another object of the invention is to provide new and novel circuit arrangements to enable a called party, when answering a call, to cut off quickly the ringing current during either the ringing or silent periods, and to provide in these arrangements a greater margin of operation over more severe subscriber line circuit conditions than is possible with the present practice of ringing cut-off relay operation. For example, in a telephone system employing party lines, a greater number of substation ringers may be bridged across a line of higher loop resistance and lower insulation resistance with the ringing cut-off method provided in the invention than with any other system of quick ringing cut-off known to the art.

A further object of the invention is to provide uniform quick ringing cut-off with all frequencies of ringing current, when party-line ringing is employed, in order that the ringing cut-off be practically instantaneous regardless of the frequency of ringing current which may be used for signalling the called substation. Under the prevailing circumstances of the art, ringing cut-off is relatively much slower with the higher frequencies of ringing current than with the lower frequencies. The invention includes new and novel means for overcoming this inequality of ringing cut-off, thereby providing for uniform quick ringing cut-off over the entire range of ringing current frequencies.

In order to accomplish the above described objects, the invention combines the control of the ringing application and the ringing cut-off functions to one relay. This combined ringing and ringing cut-off relay operates over a local circuit to supply ringing current to the selected line, and releases to disconnect the ringing current from the line when the called party answers. In addition, when the connection is completed by an operator, means are provided so that the operator starts or restarts the automatic ringing as independent operations entirely dissociated from any means for selecting the called line, the only lim-

2

iting factor being the presence of the called party on the line.

The uniformity of quick ringing cut-off on party lines is accomplished by adjusting the resistance value of the local, or holding, circuit of the combined ringing and ringing cut-off relay in direct relationship to the frequency of ringing current used in each instance. Each frequency of ringing current is allocated a certain resistance value for the holding circuit of the relay. For example, a greater resistance value is inserted in the holding circuit of the relay when 50-cycle ringing current is selected than when the ringing current is 16-cycles, in order to accomplish an equivalent quick ringing cut-off. These adjusted resistance values enable the combined ringing and ringing cut-off relay to perform uniformly and efficiently over the entire range of ringing current frequencies.

20 A feature of the invention is that the resistance value of the holding circuit of the combined ringing and ringing cut-off relay is varied by means of compensating resistances connected in series with the holding winding of the relay, the proper resistance value being selected automatically at the time the required frequency of ringing current for signalling the desired called party is selected.

Another feature of the invention is that the 30 greater margin of operation for the combined ringing and ringing cut-off relay obtained in the manner described in the preceding paragraph, provides for quicker ringing cut-off with any frequency of ringing current on a short line of 35 relatively low resistance than with any other system of quick ringing cut-off relay operation. Damage to the transmitter of the answering telephone on a low resistance line, where the ringing current flow is obviously relatively large, is, therefore, minimized because the ringing cut-off is 40 practically instantaneous when the handset of the answering telephone is lifted during a ringing period.

Another feature of the invention is that the 45 adjusting of the resistance value of the holding circuit of the combined ringing and ringing cut-off relay in direct relationship to the frequency of the ringing current used to signal the called substation, enables the power in the holding winding 50 of the combined ringing and ringing cut-off relay to offset, or neutralize, the additive effect of the alternating ringing current during the periods when the alternating current in the line winding of the relay is in the direction to aid the superimposed direct current in the line winding of the

relay. Hence, the power in the line winding of the relay does not overcome the power in the holding winding at any period and cause the relay to remain operated and continue to send ringing current out on the line after the called party has answered. Quick ringing cut-off is thus assured with any frequency of ringing current.

There are other objects and features of the invention having to do for the most part with the circuit details involved in carrying out the foregoing.

The various objects and features of the invention will be understood best upon a further perusal of the description in connection with the accompanying drawings, comprising Figs. 1 and 2, showing by means of the usual circuit diagrams so much of the apparatus in a telephone system embodying the features of the invention as are necessary to an understanding of the same.

Referring now to the drawings, Fig. 1 illustrates a cord circuit of a manual telephone switchboard utilizing the present invention. The invention may, of course, be applied to any well-known type of cord circuit equipped to perform any combination of well-known functions associated with a manual telephone switchboard.

Fig. 2, when placed below Fig. 1, shows position equipment common to all of the cord circuits of the switchboard, including the various keys, relays and operator telephone set. It is understood that the common position equipment may be of any well known type, with common key functions such as are shown on Fig. 2 of Crocker Patent 1,771,842 and described in the associated specification.

The invention having been described generally, a detailed operation of the apparatus shown will now be given. For this purpose, it will be assumed that the operator receives a call over a line circuit represented by jack J1 on Fig. 1. This line circuit may be of any well-known conventional type either common battery or local battery, the difference with respect to the cord circuit being in the resistance value of relay 10 connected to the sleeve spring of jack J1. If the subscriber line is of the common battery type, the resistance value of relay 10 will be relatively low, and if the subscriber line circuit is of the local battery type, the resistance value of relay 10 will be relatively high. The purpose of the differences in resistance values of relay 10 is to operate certain relays in the cord circuit when the line circuit is of the common battery type, and to prevent the operation of certain relays in the cord circuit when the line circuit is of the local battery type.

Assuming that the operator has received a call over a common battery line, the operator inserts the answering plug P1 of an idle cord circuit into jack J1. When the plug P1 enters the jack J1, the relay 17 of the cord circuit is energized through the sleeve of the plug and the jack and relay 19. Relay 17 operates, disconnects relay 12 from the repeating coil at contact 18, and connects the windings of relay 16 to the tip and ring conductors of the calling line through windings of the repeating coil. Relay 17 also closes the circuit of the answering cord supervisory lamp momentarily at its upper front contact. Relay 16, however, operates through the calling party telephone loop to open the answering cord supervisory lamp circuit at a back contact. Relay 16 also supplies transmission battery to the calling party. The resistance coil which is wired in multiple with the winding of relay 17 is for the pur-

pose of reducing possible shocks to the operator in the handling of the plug.

When a call is received at the jack J1 over a local battery line instead of a common battery line, sleeve relay 17 of the cord circuit does not operate when the plug P1 is inserted into jack J1 because the resistance of relay 10 is sufficiently high to prevent the operation of sleeve relay 17. The lower winding of relay 12, therefore, remains connected to the windings of the repeating coil at contact 18, and relay 16 is not connected to the repeating coil. Consequently, no transmission battery is supplied to the calling line. Relay 12 performs no function at this time.

Having inserted the plug P1 into jack J1, the operator throws the talk key of the cord circuit in order to converse with the calling party. The operation of the talk key closes the circuit 20 of splitting relay 29, the operation of which divides the cord circuit into two sections in the well-known manner, and extends both sections to the operator common position circuit shown in Fig. 2. The tip and ring of the answering plug 25 P1 are connected to the common position circuit inductively through the windings of the repeating coil and then via the upper and lower front contacts of relay 29 and conductors 60 and 61. The operator telephone set shown at the 30 left on Fig. 2 is, therefore, connected to the answering plug P1 via contact 107 of relay 104, upper winding of operator induction coil, contact 105 of relay 104, contact 112 of cut-off answer key and conductor 60 for the tip side; and via contact 101 of relay 104, lower winding of operator induction coil, contact 102 of relay 104, contact 108 of cut-off answer key and conductor 61 for the ring side. The operator may now obtain the number of the desired station from the calling party.

The operation of splitting relay 29 also switches the calling section of the cord circuit, including the sleeve conductor of calling plug P2 and the associated sleeve relay 40, to the common position circuit shown in Fig. 2, but these switchings perform no functions at this time. The resistance coil wired in multiple with the winding of relay 29 provides spark protection for the contact of the talk key.

Having ascertained the number of the desired line, the operator restores the talk key to normal and then inserts calling plug P2 into jack J2 which is assumed represents the desired line. As in the case of the line circuit connected to jack J1, the line circuit connected to jack J2 may also be of either the common battery or local battery type, and the resistance value of relay 48 connected to the sleeve spring of jack J2 will be correspondingly low or high.

The restoration of the talk key to normal position releases the splitting relay 29, and the restoring of relay 29 disconnects the common position circuit from the answering and calling sections of the cord circuit, and re-establishes the transmission circuit between the answering and calling sections of the cord circuit. Relay 29 also re-connects the sleeve of the calling plug P2 to the sleeve relay 40.

The cord circuit is equipped with a tip busy test and, consequently, in case the line circuit is of the multiple jack type, the operator may make the conventional tip busy test before inserting the calling plug P2 into jack J2. The tip busy test circuit may be traced from the sleeve of jack J2, tip of calling plug P2, contact 46 of ringing call

key, contact 42 of relay 40, conductor 58 to the common position circuit shown in Fig. 2, upper right-hand winding of the monitor and busy test coil to positive battery, and inductively to the corresponding upper left-hand winding of the monitor and busy test coil to the operator's receiver. The lower right-hand winding of the monitor and busy test coil is extended along by means of conductor 59, said conductor 59 being twisted into a pair with conductor 58 to obtain a balance so that the busy test clicks will not be introduced inductively into other cord circuits. Conductor 59 is not connected to the cord circuit.

Assuming that the selected line is of the common battery type, sleeve relay 40 is energized, 15 when the calling plug P2 is inserted into jack J2, through the sleeves of the jack and the plug and the center back contact of relay 29. The operation of sleeve relay 40 causes sleeve relay 19 to operate through contact 38, as sleeve relay 19 is of such resistance that it will operate from the relatively low resistance of relay 48 in multiple with the winding of sleeve relay 40. Sleeve relay 40 opens the tip busy test circuit at contact 42, and extends the tip conductor through contact 41 to the combined ringing and ringing cut-off relay 33.

Sleeve relay 19 disconnects relay 26 at contact 20, connects the transmission battery feed relay 23 to the inside terminals of the calling half of the repeating coil, extends ground potential from the front contact of relay 16, contact 21 of relay 19 to contact 24 of relay 23, and completes the circuit of the calling cord supervisory lamp from contact 22 through contact 37 of relay 33 and the upper back contact of relay 23.

Assuming that the desired telephone connected to jack J2 is to be signalled with the ringing frequency 2, the operator depresses momentarily the ringing key 55 all the way down, and the ringing key 55 will return to and remain in the ringing position, in the well-known manner, with its back contacts open and the front contacts closed. The first action of the downward stroke of key 55 automatically restores any of the keys 53, 54, or 56 which may be in the ringing position, and then contact 57 is operated at the bottom of the downward stroke. It is understood that the four keys 53, 54, 55 and 56 and the common contact 57 are mounted on one escutcheon and interlocked by means of a ladder releasing mechanism in the well-known manner so that only one key may be in the ringing position at one time.

The selection of frequency 2 by the operator depressing ringing button 55, causes the combined ringing and ringing cut-off relay 33 to operate from ground potential, front contact of relay 16, contact 21 of relay 19, contact 24 of relay 23, contact 51 of the ringing key, upper winding of relay 33 to negative battery, and to lock up from ground potential, front contact of relay 16, contact 21 of relay 19, contact 24 of relay 23, upper back contact of ringing key 56, upper front contact of ringing key 55, compensating resistances 51 and 52 in series, contact 34 of relay 33, upper winding of relay 33 to negative battery.

The operation of the combined ringing and ringing cut-off relay 33 connects the tip conductor of the calling plug P2 to ground potential through contact 46 of ringing call key, contact 41 of relay 40 and contact 35 of relay 33, and also connects negative-battery superimposed ringing current from the lower front contact of ringing key 55, lower back contact of ringing key 56, lower, or line, winding of relay 33, contact 32 of relay 33, contact 44 of the ringing call key to the ring con-

ductor of calling plug P2. The desired telephone on the plugged-up line is, therefore, rung automatically until either the called station answers or the calling party abandons the call. Ring-back tone is supplied to the calling party through the small-capacity condenser bridged around contact 31 of relay 33. The combined ringing and ringing cut-off relay 33 remains operated during the automatic signalling of the called station because the circuit of the direct-current component of the ringing current through the line winding of relay 33 is not closed until the called party lifts the hand-set from the telephone cradle.

The operation of the combined ringing and ringing cut-off relay 33 also opens the calling cord supervisory lamp at contact 37 thus giving the operator ringing supervision, well-known as "dark keyshelf," to indicate that the operator's work on this connection has been completed until disconnect supervision is received. Disconnect supervision will be received when the calling and called parties have completed their conversation and returned their handsets to the respective cradles.

When the called party answers, the circuit of the direct current through the lower, or line, winding of the combined ringing and ringing cut-off relay 33 is closed through the telephone loop. 30 This direct current in the line winding neutralizes the direct current in the holding winding of relay 33 and relay 33 restores to normal, removing ringing current from the line and extending the tip and ring conductors of the calling plug P2 to the repeating coil. Relay 23 operates on the called party loop to supply transmission battery, and also opens the calling cord supervisory lamp circuit at its upper back contact, thus retaining the "dark keyshelf." The transmission circuit 40 between the calling and called parties is completed inductively through the windings of the repeating coil.

If the called party should disconnect prematurely and the calling party requests the operator to reestablish the connection, the operator may restart the ringing on the called line by depressing ringing key 55 all the way down momentarily, and relay 33 will again operate and lock up and reconnect ringing current to the tip and ring conductors of calling plug P2. It is unnecessary for the operator to request the required frequency for the rering, as the ringing key used for the original ringing will remain in the ringing position (partly depressed) until later released by the depression of ringing key button 53, 54, or 56 on a new call.

When a connection requires the use of frequency 5, the operator's ringing routine is changed somewhat since there are only four ringing key buttons on the ringing key assembly comprising keys 53, 54, 55 and 56. The lever type ringing call key associated with the calling plug P2 is used for ringing the called line with frequency 5, and is mechanically associated with the button type ringing keys 53, 54, 55 and 56 in such a well-known manner that when the lever type ringing call key is operated, any of the ringing keys 53, 54, 55 or 56 that may be in the ringing position will be automatically released and restored to normal. The automatic ringing start for frequency 5 is established through contact 45 of the lever ringing call key since contact 45 of the lever ringing call key is in multiple with contact 47 of the button ringing key assembly, thus 70 operating and locking up relay 33 in a similar

manner to that described for frequency 2. The ringing circuit for frequency 5 may be traced from the lower back contacts of ringing keys 53, 54, 55 and 56, through the lower winding of relay 33, contact 32 of relay 33, ring conductor of calling plug P2, out on the line and returning over the tip conductor through contact 35 of relay 33 to ground potential.

When the called line is of the local battery type, the operator signals the desired telephone manually by means of the lever ringing call key associated with the calling plug P2. Uninterrupted generator of frequency 5 is supplied to the ring side of calling plug P2 through contact 43 of ringing call key and then out on the line and returning over the tip conductor to ground at contact 47 of ringing call key.

After the operator has completed a connection between the calling and called party, she may operate the talk key of the cord circuit to split the cord circuit into two sections and switch automatically both sections of the cord circuit to the common position circuit shown in Fig. 2, for the purpose of monitoring the established connection, talking to either party without overhearing by the other party, refunding and collecting paystation deposits, or performing any other functions that may be associated with the common position circuit. As previously explained, the operation of splitting relay 29 switches the tip and ring conductors of the answering plug P1 to the common position circuit via conductors 60 and 61. The tip and ring conductors of the calling plug P2 are switched to the common position circuit via contact 46 of the ringing call key, contact 41 of relay 40, contact 36 of relay 33, the upper make-before-break contact of relay 29 and conductor 64 for the tip side; and contact 44 of the ringing call key, contact 31 of relay 33, the lower make-before-break contact of relay 29 and conductor 65 for the ring side.

The operation of relay 29 by the talk key also connects the sleeve of the calling plug P2 to the common position circuit via the center make-before-break contact of relay 29 and conductor 63; and the sleeve relays 19 and 40 in multiple via the center front contact of relay 29 and conductor 62. The purpose of disconnecting the sleeve of the calling plug P2 from the associated sleeve relays 19 and 40 and extending both units to the common position circuit is to enable the operator to insert automatically a dial in the sleeve conductor of the calling plug P2 when the call is to be extended to an automatic switchboard. The circuit details of the dial connections have been omitted from Fig. 2 as it is understood that such details are not essential to an understanding of the invention.

Fig. 2 is equipped with cut-off keys for cutting off either the answering or calling plugs and connecting them to the operator's telephone equipment shown to the left on Fig. 2. A common monitoring key is also shown in Fig. 2 which, when operated, causes the associated switching relay 104 to connect the operator's receiver to a monitoring coil for the purpose of monitoring an established connection without materially reducing the transmission efficiency or in any way interfering with the connection. The monitoring circuit may be traced from operator receiver, upper winding of monitor coil, contact 106 of relay 104, contact 112 of cut-off answer key and conductor 60 for the tip side, and from operator receiver, contact 103 of relay 104, contact 108 of cut-off answer key and conductor 61 for the

ring side. Operating the cut-off answer key disconnects the operator telephone set at contacts 108 and 112, and places a bridge 110 across the repeating coil via conductors 60 and 61, thus enabling the operator to converse with the called party via conductors 64 and 65 without overhearing by the calling party. In a similar manner, the operator may converse privately with the calling party by operating the cut-off call key. Fig. 2 may incorporate any of the well-known common position key operations such as dial keys, refund and collect paystation keys shown in Crocker Patent 1,771,842 and any other key functions known to the telephone art.

15 Disconnect supervision is obtained on a completed connection where both the calling and called lines are common battery, when the calling and called parties restore their handsets to the respective cradles, and the transmission battery 20 feed relays 16 and 23 correspondingly restore to normal. Responsive to the releasing of relay 16, the circuit of the answering cord supervisory lamp is closed from ground potential at the upper make contact of relay 17, back contact of relay 16, answering supervisory lamp to negative battery; and responsive to the releasing of relay 23, the circuit of the calling cord supervisory lamp is closed from ground potential at contact 22 of relay 19, contact 37 of relay 33, upper back contact of relay 30 23, calling supervisory lamp to negative battery.

Disconnect supervision when the calling line is of the local battery type is obtained by the calling party turning the hand generator of his telephone. As previously explained, sleeve relay 17 35 does not operate when the answering plug P1 is inserted into jack J1 because of the high resistance value of relay 10. The lower winding of relay 12, therefore, remains connected to the repeating coil at contact 18. Ringing current 40 from the hand generator causes relay 12 to operate and close contact 15 and thereby complete the holding circuit of relay 12 from ground potential at contact 30 of relay 29, contact 15 of relay 12, upper winding of relay 12 to negative 45 battery. Responsive to the locking of relay 12, the circuit of the answering cord supervisory lamp is closed from ground potential at contact 14 relay 12, answering supervisory lamp to negative battery. The resistance coil 11 wired in multiple 50 with the upper winding of relay 12 provides spark protection for contact 15. The resistance coil 13 connected in multiple with the lower winding of relay 12 when relay 12 is locked up, provides a by-pass for subsequent ringing current to protect relay 12 from accidental ring down should sufficient ringing current pass through its lower winding to neutralize momentarily the holding current in the upper winding.

Disconnect supervision when the called line is of the local battery type is obtained by the called party turning the hand generator of his telephone. Sleeve relay 19 does not operate when the calling plug P2 is inserted into jack J2 because of the high resistance value of relay 48. The lower winding of relay 26, therefore, remains connected to the repeating coil at contact 20. Ringing current from the hand generator causes relay 26 to operate and close contact 28 and thereby complete the holding circuit of relay 26 from ground potential at contact 30 of relay 29, contact 28 of relay 26, upper winding of relay 26 to negative battery. Responsive to the locking of relay 26, the circuit of the calling cord supervisory lamp is closed from ground potential at the upper front contact of relay 26, upper back contact of relay

23, calling supervisory lamp to negative battery. The resistance coil 27 wired in multiple with the upper winding of relay 26 provides spark protection for contact 28. The resistance coil 25 connected in multiple with the lower winding of relay 26 when relay 26 is locked up, provides a by-pass for subsequent ringing current to protect relay 26 from accidental ring down should sufficient ringing current pass through its lower winding to neutralize momentarily the holding current in the upper winding. The condenser in series with the lower winding of relay 26 is provided for the purpose of preventing supervisory signal interference between a common battery line on one cord circuit and a local battery line on another cord circuit should the operator use the talk keys of both cord circuits for "over-lap" service.

A common group of five push button ringing keys shown at the lower left on Fig. 1 is multiplied to the lever ringing keys associated with the answering plugs of the cord circuits to enable the operator to rering parties on the answering plug P1. The rering is done on a manual basis only, with the operator applying the ringing current by means of the lever ringing key associated with the answering plug P1. No wiring is required on the frequency 5 ringing key, as frequency 5 is wired through the back contacts of the ringing keys associated with frequencies 1, 2, 3 and 4 to the ringing common contact on the R side of the lever ringing key. Frequency 5 ringing button is depressed when frequency 5 ringing current is required, in order to release and restore any of the ringing keys associated with frequencies 1, 2, 3 or 4 that may be in the ringing position.

The lever ringing keys associated with both the answering and calling plugs, and also splitting relay 33, are fitted with an extra front contact for starting the ringing machine whenever such well-known ringing arrangements are provided.

It should be understood that while the foregoing description and associated drawings disclose the invention as specifically used on connecting circuits of the manual switchboard cord type, the invention is not limited to such connecting circuits but may be applied to any type of connecting circuit in which automatic ringing is employed.

Having described the invention and what is considered new and desired to be protected by Letters Patent is set forth in the following claims:

What is claimed is:

1. In a telephone system, a calling and a called line, operator-controlled means for establishing a connection between said lines, a source of signalling current, a relay, operator-controlled means for operating said relay to close a signalling circuit including said source and the called line, and means effective upon the response of the called party for operating said relay in series with said line to disconnect said signalling circuit from said line.

2. In a telephone system, a calling and a called line, operator-controlled means for establishing a connection between said lines, a source of signalling current, a relay having a pair of windings, operator-controlled means for completing the circuit of one winding of said relay for causing said relay to operate and close a signalling circuit including said source, the other winding of said relay and the called line, and means effective upon the response of the called party for releasing said relay to disconnect said signalling circuit from said line.

3. In a telephone system, a called party line,

operator-controlled means for establishing a connection to said party line, a plurality of signalling current sources, means for selecting the proper source to signal a party on said line, a relay having two windings, operator-controlled means for operating said relay through one winding thereof to close a signalling circuit including said selected source, the other winding of said relay and the called line, and means controlled by the called party's response for releasing said relay to disconnect said source from the called line.

4. In a telephone system, subscribers' lines, operator-controlled means for extending a connection to one of said lines, a signalling current source including a direct current superimposed on an alternating current, a relay having two windings, operator-controlled means for energizing said relay through one winding thereof to close a signalling circuit including said source, the other winding of said relay and the called line, the alternating current component of said source supplying the power for signalling the called line, and means including the direct current component of said source and responsive to the called subscriber answering for releasing said relay to disconnect said source.

5. In a telephone system, subscribers' lines, means for extending a connection to one of said lines, a source of signalling current, a relay including a winding, a key for causing said relay to operate and complete a signalling circuit including said source, said winding and the called line, and means for releasing said relay responsive to the called subscriber answering, said signalling circuit being instantly disconnected when said relay releases.

6. In a telephone system, a called line, means for establishing a connection to said line, a signalling current source, a double-wound relay, a key for completing a circuit through one winding of said relay for causing said relay to operate and lock through said winding to close a signalling circuit for said line, said signalling circuit including said source, the second winding of said relay and the called line, and means controlled by the called party's response for causing the release of said relay to disconnect said source from said line.

7. In a telephone system, a called party line, means for establishing a connection to said party line, a plurality of signalling current sources, a plurality of keys for selecting the proper source to signal the called substation on said line, a relay having a pair of windings, a circuit controlled by any one of said plurality of keys for energizing and locking said relay through one winding thereof to close a signalling circuit including said selected source, the other winding of said relay and the called line, said relay releasing responsive to the called substation answering to disconnect said source from said line.

8. In a telephone system, a called party line, means for establishing a connection to said line, a plurality of signalling current sources, a plurality of resistances, a relay, means for selecting the proper source to signal the called substation, for selecting a portion of said plurality of resistances dependent upon the particular source selected, and for operating said relay in series with said selected portion of said resistances to close a signalling circuit including said selected source and the called line, and means controlled by the called substation's response for operating said relay to disconnect said signalling circuit.

9. In a telephone system, a called party line,

means for establishing a connection to said line, a plurality of signalling current sources, a plurality of resistances, a relay, means for selecting one of said sources to signal a party on said line, for selecting a portion of said plurality of resistances dependent upon the particular source selected, and for closing a circuit for said relay in series with said selected portion of said resistances, a signalling circuit closed by the operation of said relay, said signalling circuit including said selected source, said relay and the called line, and means effective upon the response of the called substation for releasing said relay to disconnect said source.

10. In a telephone system, a party line, means for extending a connection to said line, a plurality of signalling current sources, a plurality of resistances, a differentially-wound relay, means for selecting the proper source to signal the called substation, for selecting a portion of said plurality of resistances dependent upon the particular source selected, and for energizing said relay through one winding thereof in series with the said selected portion of said resistances, a signalling circuit closed by the operation of said relay, said signalling circuit including said selected source, the other winding of said relay and the called line, said relay releasing in response to the called station answering to disconnect said signalling circuit.

11. In a telephone system, a party line, means for extending a connection to said line, a plurality of alternating current signalling sources including a direct current superimposed on each of said plurality of sources, a plurality of resistors, a relay, means for selecting one of said sources to signal a party on said line, for selecting one or more of said resistors to form a resistance of certain value dependent upon the particular source selected, and for connecting said relay in series with said selected resistor or resistors, a signalling circuit including said selected source and the called line and closed by the operation of said relay, the alternating current component of said source supplying the power for signalling the called substation, and means including the direct current component of said source and controlled by the called station's response for operating said relay to open said signalling source.

12. In a telephone system, a party line, operator-controlled means for extending a connection to said line, a plurality of signalling current sources, a plurality of resistances, means for selecting the proper source to signal a party on said line, and for selecting a portion of said plurality of resistances dependent upon the particular source selected, a relay, operator-controlled means for closing a circuit for said relay in series with said selected portion of said resistances, a signalling circuit closed by the operation of said relay, said signalling circuit including said selected source and said line, and means effective upon the response of the called party for releasing said relay to disconnect said source from said line.

13. In a telephone system, a called party line, operator-controlled means for establishing a connection to said party line, a plurality of signalling current sources, a plurality of resistances, a relay, operator-controlled means for selecting the proper source to signal the called substation, for selecting a portion of said plurality of resistances dependent upon the particular source selected, and for closing a circuit for said relay in series

with said selected portion of said resistances, and a signalling circuit closed by the operation of said relay and including said selected source, said relay and the called line.

14. In a telephone system, a called party line, operator-controlled means for establishing a connection to said line, a plurality of signalling current sources, a plurality of resistors, a plurality of keys for selecting one of said sources to signal a party on said line, and for selecting one or more of said resistors to form a resistance of certain value a relay, a circuit controlled by any one of said plurality of keys for operating said relay in series with said selected resistor or resistors, a signalling circuit closed by the operation of said relay and including said selected source and said line, and means controlled by the called substation's response for operating said relay to disconnect said source.

15. In a telephone system, a party line, means for extending a connection to said line, a plurality of signalling current sources, a plurality of resistors, a plurality of keys for selecting different sources to signal different stations on said line, and for selecting one or more of said resistors dependent upon the particular source selected, a relay, a circuit controlled by any one of said keys, a signalling circuit closed when said relay is energized in series with said selected resistor or resistors over said operating circuit responsive to the operation of one of said keys, said signalling circuit including said selected source, said relay and the called line, and means effective upon the called station's response for releasing said relay to open said signalling circuit.

16. In a telephone system, a party line, means for extending a connection to said line, a plurality of signalling current sources, a plurality of resistors, a plurality of keys for selecting different sources to signal different stations on said line, and for selecting portions of said resistors dependent upon the particular source selected, a double-wound relay, a circuit controlled by any one of said keys for energizing and locking said relay through one winding thereof in series with said selected portion of said resistors, a signalling circuit closed by the operation of said relay and including said selected source, the other winding of said relay and the called line, and means controlled by the called station answering for releasing said relay to disconnect said source from said line.

17. In a telephone system, a called party line, means for establishing a connection to said line, a plurality of alternating current signalling sources including a direct current superimposed on each of said plurality of sources, a plurality of resistors, a plurality of keys for selecting different sources to signal different stations on said line, and for selecting portions of said resistors to form resistances of certain values dependent upon the different sources selected, a relay, a circuit controlled by any one of said plurality of keys for causing said relay to be energized in series with a particular selected resistance value, and a signalling circuit closed by the operation of said relay and including said selected source and the called line, said signalling circuit being disconnected when said relay releases responsive to the called station answering.

18. In a telephone system, a called party line, means for establishing a connection to said line, a plurality of signalling current sources, a plurality of resistances, a differentially-wound relay, a balancing circuit including one winding of said

13

relay, means for connecting different ones of said sources to said line through the other winding of said relay to signal different stations on said line, and for connecting different values of resistance in series with said balancing circuit to compensate for different sources connected to the other winding of said relay.

19. In a telephone system, a party line, means for extending a connection to said party line, a plurality of signalling current sources, a plurality of resistances, a differentially-wound relay, a balancing circuit including one winding of said

14

relay, means for connecting any of said sources to said line through the other winding of said relay to signal a party on said line, and for connecting the proper value of resistance in series with said balancing circuit for providing the proper power in the balancing circuit winding of said relay to neutralize the power developed in the other winding of said relay when the called party answers, said neutralization causing the release of said relay to disconnect said source.
